PAD FOLDING MACHINE

Oscar T. Thompson, Neenah, Wis., assignor, by
mesne assignments, to International Cellu-
cotton Products Co., Chicago, Ill., a corpora-
tion of Delaware

Application November 15, 1926, Serial No. 148,322

24 Claims. (Cl. 154—29)

This invention relates to pad folding machines, and more specifically to machines for folding flaps which project from the ends of an article and for folding the flaps upwardly and inwardly over the article to prepare the same for packaging in a convenient form for vending. The present invention has particular reference to a machine for folding the projecting ends of the wrapper of a catamenial bandage such as is produced by a machine disclosed in the co-pending application of William Bauer, for Pad making machines, Serial No. 687,012, filed January 18, 1924.

The objects of the present invention are: to provide a machine which will automatically fold the projecting end flaps of a package over the respective ends of the article so as to produce a compact package which may be readily wrapped in a suitable wrapper and conveniently handled for vending; to provide means incidental to the folding operation for pressing or compressing the article so as to reduce the thickness thereof; to provide a machine for carrying out the above objects which may be connected to the machine of the above mentioned co-pending application and operated as a unit thereof and to eliminate handling of the articles, and in general, to provide an improved machine of the class described. Other objects and advantages will become apparent when reference is had to the following specification when considered in connection with the accompanying drawings wherein I have illustrated a selected embodiment of my invention in which:—

Fig. 1 is a side elevation.

Fig. 2 is a plan.

Figs. 3 and 4 are sections on the lines 3—3 and 4—4 respectively of Fig. 1.

Fig. 5 is a section on the lines 5—5 of Fig. 2.

Fig. 6 is a section similar to Fig. 5, but showing the parts in another position.

Fig. 7 is a diagrammatic illustration showing the means for folding one of the end flaps.

Fig. 8 is a perspective of the folding elements.

Fig. 9 is a perspective of the article after the end flaps are folded.

Fig. 10 is a side view, partly in section on the line 10—10 of Fig. 11, of a pad making machine with which my folding machine may be associated and Fig. 11 is a view of the pad making machine taken on the line 11—11 of Fig. 10, certain parts being shown in section to facilitate illustration.

My present invention involves the provision of suitable pad folding mechanism which is particularly adapted to folding the end flaps or tabs

of sanitary napkins such as are produced by a machine made according to the invention and application of William Bauer above referred to, and my invention includes the combination of such a pad making machine with my improved tab folding mechanism whereby sanitary napkins may be automatically produced and delivered in condition for packing in boxes or cartons.

For the purpose of my present application, a brief description of a suitable pad making machine and its operation will be sufficient to enable others skilled in the art to understand the manner in which my tab folding mechanism cooperates with the pad making mechanism, and hence I will proceed to describe only briefly the pad making mechanism invented by the said William Bauer and illustrated in Figs. 10 and 11.

In Fig. 10, a supply roll of suitable pad covering material such as gauze is indicated at 1, the same being rotatably supported in any suitable manner by means of supporting frame work 2. From the supply roll 1, the strip 3 of gauze is drawn and fed forward by suitable feeding means including a belt 4 and pressure roll 4', the said belt being positively driven by any convenient means and from any suitable source of power. The supply strip 3 of covering material is carried by the belt 4 longitudinally over the top of a supporting table as clearly shown from the delivery end of which, the gauze is directed downwardly over an inclined chute 10' (see Fig. 1).

A supply roll of suitable absorbent pad material is indicated at 5 in Fig. 11, and means including an intermittently actuated feed belt 6 is provided for advancing the supply strip 7 of pad material, the same being drawn from the supply roll as will be readily understood from an inspection of the said Fig. 11. The forward end portions of the strip of pad material 7 are successively severed therefrom by means of a motor 35 driven circular saw 8 which is reciprocated vertically in properly timed relation to the advancement of the supply strip. The strip is advanced a predetermined amount each time the feed device 6 is actuated, and hence the saw 8 will operate to cut off a pad of predetermined width each time the saw is moved downwardly into cutting engagement with the pad strip.

For supporting the forward end of the pad strip while the said forward end is being severed from the supply strip, there is provided a horizontally reciprocable table 9. A stationary stripper member 9a serves to strip the severed pad from the table 9 when the latter is moved outwardly to the position shown in Fig. 11, and a

plurality of forwardly and downwardly inclined fingers 9b are provided for insuring proper deposition of the severed pad sections on the cover strip 4 which is traveling in a direction extending crosswise of the direction of feed of the pad supply strip 7.

The pad supply strip 7, in the pad-making machine above described, is of a width substantially equal to the length of the desired pad sections 10 and the length of the front end portions of the strip which is cut therefrom constitutes the width of the severed pad. In the pad-making machine 15 above described, the cover material strip 3 is of greater width than the width of the pad supply strip 7, as will readily be understood from a comparison of the width of the respective supply strips as shown in Figs. 10 and 11. However, the pad sections which are severed from the supply strip 7 are of an even smaller width than the 20 width of the supply strip 7 so that the pad section is oblong in shape. The pads are deposited in longitudinally spaced relation on the strip of covering material intermediate the width of the latter so as to leave marginal side portions of 25 gauze projecting sidewise from the opposite side edges of the pad. Such deposition of the pads is effected as an incident to the continuous travel of the covering strip while the pad supply strip is advanced intermittently and pad sections severed therefrom at predetermined intervals to control the spacing between the pads disposed on the covering strip.

Suitable folding devices 9c are provided along the table over which the covering material strip 35 is fed, these folding devices being of the type which directs or folds the marginal side portions of the covering strip upwardly and transversely over the top of the median portion of the covering strip and over the top faces of the longitudinally spaced pad sections.

The details and the mechanism for actuating the above described pad making mechanism are fully described in the said copending application of William Bauer, and since such details of construction and operation do not constitute a part 45 of my invention, the same need not be more fully described herein.

It will be seen that the pad making machine above described serves to deliver a series of connected sanitary napkins to an inclined chute 10' and a rotary cutting or shearing mechanism indicated at 11 (Fig. 1) is provided for severing the napkins intermediate successive pads so as to form end flaps or tabs 22-22 for each pad. 50 The chute 10' and cutting unit 11 is suitably supported on a frame element 10 as clearly shown in Fig. 1, and the details of the cutting mechanism 11 are fully disclosed in the above referred to application of William Bauer. The details of the 55 cutting mechanism were not invented by me, and hence a detailed description thereof need not be given. Suffice it to say that any form of cutting mechanism adapted to the purpose may be used.

The pad making machine delivers a pad which 60 consists of a pad of soft filling material wrapped with a covering of gauze or the like and as clearly illustrated in Figs. 1 to 5, the ends of the wrapper form flaps which project beyond the respective ends of the filler pad. As the pads are 65 delivered from the pad making machine, they are received, according to the present invention, on a continuously moving conveyor belt 12 which extends around suitable rolls 13 and 14 which are provided with shafts 15 and 16 respectively. The shaft 15 of the roll 13 is journaled in suitable

bearings in the frame 10 and the shaft 16 of the roll 14 is journaled in suitable bearings in the frame 17 which supports the folding mechanism of the present invention. The shaft 15 extends outwardly on both sides of the roll 13 and is provided with a pair of sprocket wheels 18-18, one on each side of the roll 13, and is adapted to turn with the roll. The sprocket wheels 18-18 receive a pair of sprocket chains 19-19 which are also threaded over a pair of sprockets 20-20 at the other end of the machine. It will be apparent that the chains 19-19 and the conveyor belt 12 are adapted to travel together at the same speed, since the roll 13 and the sprocket wheels 18-18 are of a size to produce this result. 15 Suitable means may be provided for maintaining the chains taut and may comprise bell cranks 19a pivotally mounted on the frame 17 and having an idler pulley mounted at the end of one leg and adapted to engage the lower reach of the chain 20 and having a weight suspended from the end of the other arm as shown in Fig. 1. The chains 19-19 are connected at intervals by means of flap receiving members 21 which, as clearly shown in Fig. 1, are adapted to receive the flaps 25 22-22, at the ends of the pads 23, thereover as the pad is delivered to the conveying belt from the cutting mechanism 11.

The conveyor belt 12 is adapted to deliver the pad to a supporting conveyor belt 24 which extends around suitable drums 25 and 26 which are each rotatably mounted in suitable bearings on the frame 17. The supporting conveyor belt 24 is adapted to be intermittently moved and for this purpose I provide the following mechanism. 30 The shaft 27 of the drum 25 extends outwardly beyond its bearings as best shown in Figs. 2 and 4. A sprocket wheel 28 is rotatably mounted on the projecting end of the shaft 27 and is provided with a ratchet tooth faced hub 29. The 40 sprocket wheel 28 is driven from any suitable source of power and in the present instance I contemplate driving this sprocket by means of a chain 30 (Fig. 1) which is threaded over a suitable sprocket wheel 31 which, in turn, is mounted 45 on and secured to the shaft 32 of the sprockets 20-20. The shaft 32 may be rotated by suitable means such as a sprocket 33 secured thereto and adapted to receive a chain which may be driven from any driven power shaft. It is, of course, 50 obvious that I may apply the driving power at either end of the machine, for instance, as above explained, to the shaft 32, or to the shaft 15 or to any other suitable shaft.

Rotation is transmitted from the sprocket wheel 28 to the shaft 27 by means of a clutch member 34 which is axially slidable but non-rotatably mounted on the projecting end 35 of the shaft 27. A coil spring 36 interposed between the outer face of the clutch member 34 and a collar 37 secured to the outer end of the projection 35 normally urges the clutch member 34 into engagement with the ratchet tooth face 29 of the sprocket 28. The clutch member 34 is intermittently forced out of engagement with the ratchet tooth face 29 by means of a forked arm 38 which straddles a portion of the clutch member 34 and engages the opposite faces of the groove 39 in the clutch member. The forked arm 38 is secured to a rock shaft 40 journaled at one end in a bracket 41 secured to the frame 17 and at its other end in a bracket 42 secured to the frame 10. The rock shaft 40 may conveniently be rocked by means of a cam arm 43 secured thereto and adapted to be rocked by means of a rotating cam

44. The rotating cam 44 is preferably secured to the shaft 15 so as to rotate therewith. It will be apparent that when the cam 44 forces the cam arm 43 inwardly (Fig. 2), the forked arm 38 will cause the clutch member 34 to be disengaged from its cooperating member, whereby movement of the supporting conveyor 24 will be stopped.

In the apparatus thus far described, the conveyor belt 12 is adapted to receive the pad with its flaps extending from its ends from the pad making machine and the flap receiving members receive the respective end flaps thereover. The conveyor belt 12 is continuously driven by the above described chain driving means through the 15 sprocket 33, shaft 32, and sprockets 20—20 over which the chains 19 are threaded and through which chain the roll 13 is driven by means of the sprocket 18 secured to the shaft 15 as above described. Suitable means such as a gear train 20 comprising gears 10, 71 and 72 is provided to synchronize the movement of the cutting mechanism 11, conveyor 12 and chains 19—19, so that the conveyor and flap-receiving means 21 on the chains 19—19 will always be brought into proper 25 position to receive the pads as they are severed and discharged from the pad making machine.

The conveyor 12 carries the article or pad forwardly to the intermittently driven supporting conveyor 24. When the article is delivered and is 30 properly positioned on the supporting conveyor 24, the latter is stopped. The conveyor 12, however, and the chains 19—19 with their connecting cross members or flap receiving members 21 continue to move forwardly. During the continued 35 forward movement of the flap receiving members 21, they are guided in a path inclined upwardly relative to the plane of the conveyors 12 and 24. This is accomplished by means of guides 45 which are supported by the frame 17 and on which the 40 respective chains 19—19 ride as best shown in Fig. 1.

When the rear flap receiving member 21 reaches the position shown in Fig. 5 adjacent the rear end of the pad, it will have been raised to 45 a position somewhat higher than the top of the pad and will be in a position to ride over the top of the pad whereby it will carry the rear end flap inwardly and over the pad as will be readily understood from an inspection of Fig. 6. When the member 21 has reached a position over the rear end of the pad, the guide members 45 are inclined downwardly so as to cause the member 21 to be lowered into contact with the top of the pad. The chains 19 are caused to follow the 50 guide 45 downwardly by means of guides 65—65 which ride over the tops of the chains as best shown in Figs. 1 and 4. By this means the flap is pressed tightly against the top surface of the pad and the pad itself is somewhat compressed and smoothed out. Further movement of the 55 chains 19—19 and of the flap receiving member 21 carries the member 21 upwardly over a folder 46 and around the sprocket 20. As the member 21 leaves the pad, the supporting conveyor 24 is set into motion so as to advance the pad whereby 60 folding of the forward flap is accomplished.

The folder 46 comprises a top plate 47 having depending side flanges 48—48 which are angularly inclined from a wide forward end to a narrow rear end. The folder 46 is stationarily 65 mounted by suitable brackets 49 on a bed plate 50 which is supported by means of the frame 17 and brackets 51—51 secured thereto. As will be understood from an inspection of Figs. 5 and 6, forward movement of the conveyor 24 carries

the pad forwardly under the folder 46. The forward end flap 22 which has previously been deposited on the top of the folder, when the corresponding flap receiving member 21 is carried thereover, is folded upwardly and inwardly over the corresponding end of the pad, and where the flaps are of sufficient length, over the first folded flap. The top 47 of the folder is preferably inclined downwardly so as to press the forward end flap closely against the top of the pad as it 10 moves thereunder and the depending side flanges 48 are operative to square up the side edges of the pad. As the pad is propelled through the last folding operation, it is delivered to another receiving conveyor 52 which is adapted to convey 15 the article to a packing machine or any other desired receiving means.

As the pads are received from the pad making machine, the flaps project from the ends thereof and from both the top and bottom sides of the 20 pad. I find it desirable to crease the flap adjacent the end of the pad so as to effect a cleaner or sharper fold and for this purpose I provide a creasing bar 53 which is carried by a sprocket 54 rotatably mounted on a suitable bracket 55, 25 carried by the frame 17. The sprocket 54 meshes with one of the chains 19 and is thereby rotated. The creasing bar 53 is mounted in such a position on the sprocket that as the sprocket rotates, the bar will engage the forward flap 22 closely adjacent the front end of the pad and will be operative to force the flaps downwardly adjacent the forward end of the pad into a position substantially as shown at the right hand end in Figs. 5 and 6. It will be apparent that when the 30 forward end flap is turned upwardly and inwardly over the pad that the initial fold will be along the lower front edge of the pad and that the flap will then lie closely and smoothly over the end and top of the pad. It will be understood that 35 the creasing mechanism just described may be so timed as to effect creasing of the flap at the rearward end of the pad instead of the one at the front end, and also that the same mechanism could be duplicated if it be desired to crease both 40 end flaps.

For insuring the proper positioning of the pad on the supporting conveyor 24 and for improving the creasing of the flap at the forward end of the pad, I provide a member 56 which extends 50 across the width of the pad and is mounted on a rod 57 which is pivotally supported by a pair of brackets 58—58 which are supported by the frame. The rod 57 is adapted to be rocked in its bearings by means of an arm 59 and connecting 55 rod 60 which is pivotally connected by means of a crank pin 61 to a collar 62 secured to the rotary shaft 63 of the cutting mechanism 11. As the collar 62 rotates, the rod 60 is reciprocated and the shaft 57 thereby rocked. The member 60 60 being secured to the shaft 57 is thereby swung upwardly and downwardly into positions as indicated in Figs. 5 and 6. When in the position shown in Fig. 5, it is operative to prevent forward movement of the pad due to frictional engagement of the folding member or flap receiving member 21 or other causes and it also further creases the forward end flap adjacent the forward end of the pad. Movement of the member 65 65 is of course properly timed with the movement of the intermittently operated supporting conveyor 24 so as to permit forward movement of the pad when the conveyor is moved to advance the pad. Adjustment of the member 56 may be had by moving the brackets 58 upwardly 70 75

or downwardly and for this purpose I mount the brackets 58—58 on the side frames by means of a clamping screw 64 which passes through a suitable slot in respective brackets and threadedly 5 engages the frame.

While I have found that frictional engagement between the supporting conveyor belt 24 and the pads 23 is ordinarily sufficient to cause the pad to move with the conveyor or to stop therewith, 10 I may provide additional means for insuring more positive engagement therebetween. Such means may comprise a plurality of small pins projecting upwardly from the conveyor 24 and adapted to engage the bottom of the pad.

15 I have thus provided a machine of the character described which is simple in construction having few parts and without delicate adjustments and which is, therefore, not apt to become out of working order and which is entirely automatic in its operation. I am aware that various 20 changes in construction, proportion, and arrangement of parts may be made without departing from the essence of the invention as defined by the following claims which I desire to have construed as broadly as possible, consistent with the 25 state of the art.

I claim as my invention:

1. In a machine for folding a flap over the end 30 of a package from which it projects, the combination of an intermittently movable supporting member, a continuously driven feed conveyor adapted to receive the package with the flap unfolded and to feed same endwise to said supporting member, independent means movable with said conveyor and also movable relative thereto and to said supporting member and having means for receiving the flap thereover, means for causing said flap receiving means to move upwardly relative to the package and thereover whereby the flap is folded upwardly and inwardly over the package.

2. In a machine for folding flaps which project from opposite ends of a package, an intermittently movable supporting member, a continuously driven feed conveyor adapted to receive the package with its flaps unfolded and to feed same endwise to said supporting member, independent means movable with said conveyor and also movable relative thereto and to said supporting member and having means for receiving one of the flaps of the package thereover, means for causing said flap receiving means to move upwardly relative to the package and thereover whereby the corresponding flap is folded upwardly and inwardly over the package, said folding operation 50 being effected during a period of rest of said supporting member, and means for folding the other end flap upwardly and inwardly over the adjacent end of the package as an incident to succeeding 55 movement of the package with the supporting member.

3. In a machine for folding flaps which project from opposite ends of a package, the combination of an intermittently movable supporting member, a continuously driven conveyor adapted to successively receive the packages having flaps projecting from their opposite ends and to successively deposit the same on said supporting member, independent means movable with said conveyor and having means for receiving the flaps thereover, means for causing one of said flap receiving means to move upwardly relative to the package on said supporting member and over the same whereby the corresponding flap is folded 60 upwardly and inwardly over the package, said

folding operation being effected during a period of rest of said supporting member, means for creasing the forward end flap adjacent the forward end of the package, and means for folding said forward end flap over the package at the 65 crease.

4. In a machine for folding flaps which project from opposite ends of a package, the combination of an intermittently movable supporting member, a continuously driven conveyor 10 adapted to successively receive the packages having flaps projecting from their opposite ends and to successively deposit the same on said supporting member, independent means movable with said conveyor and having means for receiving the 15 flaps thereover, means for causing one of said flap receiving means to move upwardly relative to the package on said supporting member and over the same whereby the corresponding flap is folded upwardly and inwardly over the package, said 20 folding operation being effected during a period of rest of said supporting member, means for creasing the forward end flap adjacent the forward end of the package, and means for folding the forward end flap at the crease and over the 25 corresponding end of the package as an incident to forward movement thereof on the succeeding movement of the supporting member.

5. In a machine for folding flaps which project from opposite ends of a catamenial bandage, 30 the combination of a supporting conveyor, means for intermittently moving said conveyor, a continuously driven conveyor for feeding the bandages with their flaps unfolded to said supporting conveyor, means for successively delivering the 35 unfolded bandages to said continuously driven conveyor, means for synchronizing the operation of said delivery means and said continuously driven conveyor so as to cause the bandages to be delivered to the conveyor in predetermined 40 position thereon, means movable with the last mentioned conveyor and projecting transversely thereover for receiving one end flap, means for guiding said flap receiving means upwardly relative to the bandage whereby the flap receiving 45 means is caused to move over the bandage on the supporting conveyor during a period of rest of the latter and thereby fold the rear flap over the adjacent end of the bandage, and means for folding the other end flap over the other end of 50 the bandage.

6. In a machine for folding flaps which project from opposite ends of the pad portion of a catamenial bandage, the combination of a feed conveyor, an intermittently driven supporting conveyor adapted to receive the bandages from said feed conveyor, means for positioning the bandages on said supporting conveyor, means movable over both said feed conveyor and supporting conveyor for receiving the flaps thereover, means for creasing the forward end flap adjacent the corresponding end of the pad portion of the bandage, means for guiding the rear flap receiving means upwardly and over the bandage on the supporting conveyor during a period of rest thereof, 65 whereby the rear flap is folded, said flap receiving means being adapted to compress the bandage as it moves thereover, and means for folding the forward end flap at the crease and upwardly and inwardly over the corresponding end of the 70 pad portion and operable as an incident to the forward travel of the bandage on the supporting conveyor after the first mentioned folding operation.

7. In a machine of the class described, the 75

combination of mechanism for severing catamenial bandages successively from the end of a continuous series of such bandages connected together by their adjacent end flaps and continuously fed endwise, mechanism independent of said severing mechanism for propelling the bandages successively away from said severing mechanism so as to facilitate successive operation of the latter to sever the succeeding bandages from the series, and mechanism for folding the severed end flaps of the bandages over the ends thereof.

8. In a machine of the class described, the combination of mechanism for severing catamenial bandages successively from the end of a continuous series of such bandages connected together by their adjacent end flaps and continuously fed endwise, mechanism independent of said severing mechanism for propelling the bandages successively away from said severing mechanism so as to facilitate successive operation of the latter to sever the succeeding bandages from the series, and mechanism for folding the severed end flaps of the bandages over the ends thereof, which includes an end flap support movable relative to the propelling means.

9. In a machine of the class described, the combination of means for successively severing bandages from the end of a continuous series, a belt conveyor for receiving the severed bandages from said severing means and propelling the body portions of the severed bandages endwise with flaps extending endwise from its opposite ends, and end flap supporting members associated with said conveyor but movable relative thereto for folding said end flaps over the adjacent ends of the bandages.

10. In a machine of the class described, the combination of means for propelling bandages endwise, means for successively feeding the bandages to said propelling means, and means independently movable longitudinally of said propelling means in a direction substantially parallel to the direction of movement of the latter for folding one of the end flaps of the bandages over the adjacent ends of the bandages.

11. In a machine of the class described, the combination of a conveyor for propelling catamenial bandages endwise, means for feeding the bandages successively to said conveyor, and means independently movable longitudinally of said conveyor in a direction substantially parallel to the direction of movement of the latter for receiving one of the end flaps of a bandage as it is delivered to said conveyor and operative to fold the flap over the adjacent end of the bandage.

12. In a machine of the class described, the combination of a movable support for receiving and supporting a catamenial bandage having a pad portion and a wrapper therefor of gauze, said wrapper being of greater length than the length of the pad so as to form end flaps extending endwise from the opposite ends of the pad, said flaps being limp and of such length that, when unsupported, they droop of their own weight from the ends of the pad, and means associated with said movable support for folding said limp end flaps upwardly and inwardly over the top faces of the respectively adjacent end portions of the pad.

13. In a machine of the class described, the combination of a conveyor, means for successively depositing on said conveyor individual, unconnected catamenial bandages having unfolded end flaps of limp textile material, said bandages being

deposited on said conveyor one by one in spaced relation, means initially movable in unison with said conveyor for receiving one of said unfolded end flaps and located so as to engage the flap adjacent the end of the body portion of the bandage from which the flap projects, and means for subsequently effecting movement of said flap-receiving means longitudinally over the body portion of said bandage, thereby to fold said end flap over the top of said body portion.

14. In a machine for folding flaps which project in opposite directions from the opposite ends of a package, a support for the package intermittently movable in a substantially horizontal direction, means for successively feeding to said support a plurality of packages having said oppositely projecting end flaps, means for folding the flap at one end over the top surface of the adjacent end portion of the package while the latter is disposed on said support and while the support is at rest, and means for folding the other flap over the top surface of the other end portion of the package while said support is in motion.

15. In a machine for folding flaps which project endwise in opposite directions from the opposite ends of a package, the combination of an intermittently movable support for the package, a continuously driven conveyor for successively feeding to said support a plurality of packages having such end flaps, and means for folding one of the end flaps of the package on said support over the top surface of the adjacent end portion of the package during a period of rest of said support.

16. In a machine for folding flaps which project endwise in opposite directions from the opposite ends of a package, the combination of an intermittently movable supporting conveyor, a continuously driven feed conveyor for successively feeding to said supporting conveyor a plurality of packages having said endwise projecting flaps, means for folding one end flap of a package on said supporting conveyor over the upper face of the adjacent end portion of the package and operable during a period of rest of said conveyor, and means for folding the other end flap over the upper face of the other end of the package as an incident to forward movement of the package on the supporting conveyor.

17. In a machine for making sanitary napkins, the combination of means for feeding a strip of cover material, means for feeding a strip of pad material, means for dividing said strip of pad material into individual pads of less width than the width of said strip of cover material, means for depositing said pads in longitudinally spaced relation on said strip of cover material intermediate the side edges of the latter, means for folding the side marginal portions of said cover material strip over said pads, means for severing said folded cover strip intermediate successive pads so as to form tabs of cover material extending endwise from each pad, and means for folding said tabs over the respective pads.

18. In a machine for making sanitary napkins, the combination of means for feeding a strip of cover material, means for feeding pad material in a continuous strip of less width than the width of said cover material strip, means for dividing said strip of pad material into individual pads of less width than the width of said strip of cover material, means for depositing said pads in longitudinally spaced relation on said strip of cover material and intermediate the side edges of the latter, sta-

- tionary means for folding the marginal side portions of said cover material strip over said pads as an incident to the travel of said cover material and pads, means for severing said folded cover strip intermediate successive pads so as to form tabs of cover material extending endwise from each pad, and means movable relative to the pads for folding said tabs over the respective pads.
- 5 19. In a wrapping machine, the combination of means to feed a continuous strip of wider cover material, means to feed a continuous strip of narrower pad material, means to sever said strip of pad material into individual pads, means to deposit said pads in lengthwise spaced relation on said strip of cover material, means to fold the longitudinal sections of said cover material over such pads, means to sever said strip of cover material between said pads, and means to fold 10 the two ends of each such individual cover over on to its pad.
- 10 20. In a wrapping machine, the combination of means to feed a continuous strip of wider cover material, means to feed a continuous strip of narrower pad material, means to sever said strip of pad material into individual pads, means to deposit said pads in lengthwise spaced relation on said strip of cover material, stationary means to fold the longitudinal sections of said traveling 15 cover material over such pads, means to sever said strip of cover material between such pads, and movable means to fold the two ends of each such individual cover over on to its pad.
- 20 21. In a machine for making sanitary napkins, the combination of means for feeding a continuous strip of cover material, means for supplying and depositing absorbent pads successively in spaced relation on said cover material, means for folding said cover material so as to enclose the 25 series of said spaced pads, means for successively severing said cover material intermediate adjacent pads, thereby to form a tab of cover material extending rearwardly from one pad and a tab of cover material extending forwardly from the following pad, and means for folding said tabs over the respective pads comprising means 30 for propelling the covered pad, and a relatively stationary element adapted to be engaged by the forwardly extending tab and adapted to wipe said tab rearwardly to folded position on a face of the covered pad as an incident to the travel of the 35 latter.
- 25 22. In a machine for making sanitary napkins, the combination of means for feeding a continuous strip of cover material, means for supplying and depositing absorbent pads successively in spaced relation on said cover material, means for folding said cover material so as to enclose the 40 series of said spaced pads, means for successively severing said cover material intermediate adjacent pads, thereby to form a tab of cover material extending rearwardly from one pad and a tab of cover material extending forwardly from the following pad, and means for folding said tabs over the respective pads comprising means for propelling the covered pad, a relatively stationary 45 element adapted to be engaged by the forwardly extending tab and adapted to wipe said tab rearwardly to folded position on a face of the covered pad as an incident to the travel of the latter, and a member movable forwardly relative to the 50 covered pad adapted to carry said rearwardly extending tab progressively from its inner end to its outer end into folded position on a face of the covered pad.
